UNITED STATES PATENT OFFICE.

WINSLOW M. BRACKETT, OF MINNEAPOLIS, MINNESOTA.

DUST AND SALVAGE CORNICE-CURTAIN.

SPECIFICATION forming part of Letters Patent No. 225,101, dated March 2, 1880.

Application filed July 15, 1879.

To all whom it may concern:

Be it known that I, WINSLOW M. BRACKETT, of the city of Minneapolis, county of Hennepin and State of Minnesota, have invented 5 a new and useful Improvement, which I have named the "Dust and Salvage Cornice-Curtain;" and I do hereby declare that the following is a full, clear, and exact description thereof, reference being had to the accompanying 10 drawings, and to the letters of reference marked thereon, making a part of this specification.

This invention relates to providing a galvanized-iron or other metal cornice for the top 15 of shelves or against walls, the interior of said cornice having a curtain-roller, the curtain for which is to be of water-proof material, and so arranged that each section of the curtain laps over its companion, thus making it a continuous 20 curtain, so that goods are protected from damage when water is thrown into the store during a fire. The metal cornice at the top extends through the plaster and lath, and has sufficient declination to permit the water to 25 flow without coming in contact with the wall. The roof of the cornice is continuous and answers as a conductor for the water to each end of the shelving or wall.

The curtain, when drawn down, protects the 30 goods from both dust and water, and being so arranged as to be practically continuous, a dis-

charge of water against the curtain could not injure the goods on the shelves.

It will be observed that the curtain is entirely hidden from sight when not in use.

The drawings are lettered as follows: A represents the cornice, provided with two rolls, B C, showing how the laps are made. D exhibits the curtain when down.

The projection of the roof of the cornice is 40 shown in A, and will be observed to pass through both the plaster and lath.

This arrangement properly put up will be neat and very serviceable, at all times a protection against dust, and in case of fire it will 45 be found very useful as a salvage-curtain.

What I claim is—

The combination, with a cornice arranged at the top of a room or set of shelves, of a series 50 of curtains arranged to be rolled within and unrolled from the cornice, and in the latter case to lap one upon another, to form a continuous protection for goods, as and for the purposes set forth.

In testimony that I claim the foregoing I 55 have hereunto set my hand and seal this 17th day of June, A. D. 1879.

WINSLOW M. BRACKETT. [L. S.]
